UNITED STATES PATENT OFFICE.

FRANK L. LEYSER, OF DES MOINES, IOWA.

DESIGN FOR A NECK-COLLAR SUPPORTER.

No. 39,832.

Specification for Design.

Patented Feb. 16, 1909.

Application filed December 5, 1908. Serial No. 466,198. Term of patent 7 years.

To all whom it may concern:

Be it known that I, FRANK L. LEYSER, a citizen of the United States, residing at Des Moines, in the county of Polk and State of Iowa, have invented a new, original, and ornamental Design for Neck-Collar Supporters, of which the following is a specification, reference being had to the accompanying drawing, forming part thereof.

The figure is a side elevation of a neck collar supporter, showing my new design.

I claim:

The ornamental design for a neck collar supporter, as shown.

FRANK L. LEYSER.
